CLAIM

The ornamental design for a printer as shown and described.

DESCRIPTION

FIG. 1 is a top perspective view of a first embodiment of a printer showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a top perspective view of a second embodiment of a printer showing my new design;

FIG. 9 is a bottom perspective view thereof;

FIG. 10 is a front elevational view thereof;

FIG. 11 is a rear elevational view thereof;

FIG. 12 is a left side view thereof;

FIG. 13 is a right side view thereof;

FIG. 14 is a top plan view thereof;

FIG. 15 is a top perspective view of a third embodiment of a printer showing my new design;

FIG. 16 is a bottom perspective view thereof;

FIG. 17 is a front elevational view thereof;

FIG. 18 is a rear elevational view thereof;

FIG. 19 is a left side view thereof;

FIG. 20 is a right side view thereof; and,

FIG. 21 is a top plan view thereof.

The broken lines depict portions of the printer that form no part of the claimed design.

1 Claim, 21 Drawing Sheets
